UNITED STATES PATENT OFFICE

171,204

LAMP

Alva S. Hess, Hopkinsville, Ky.

Application June 25, 1953, Serial No. 25,655

Term of patent 7 years

(Cl. D48—20)

To all whom it may concern:

Be it known that I, Alva S. Hess, a citizen of the United States, residing at Hopkinsville, in the county of Christian, and State of Kentucky, have invented a new, original and ornamental Design for a Lamp, of which the following is a specification, reference being had to the accompanying drawing, forming part thereof.

The characteristic features of my design are shown in full lines.

I claim:

The ornamental design for a lamp, as shown and described.

ALVA S. HESS.
